US00D883419S

(12) **United States Design Patent** (10) **Patent No.:** **US D883,419 S**
Windfeldt (45) **Date of Patent:** **** May 5, 2020**

(54) **STOCK FOR A GUN**(71) Applicant: **Michael G. Windfeldt**, St. Augusta, MN (US)(72) Inventor: **Michael G. Windfeldt**, St. Augusta, MN (US)(73) Assignee: **Maxim Defense Industries, LLC**, St. Cloud, MN (US)(***) Term: **15 Years**(21) Appl. No.: **29/662,477**(22) Filed: **Sep. 5, 2018****Related U.S. Application Data**

(63) Continuation-in-part of application No. 29/616,516, filed on Sep. 6, 2017.

(51) **LOC (12) Cl.** ..... **22-01**(52) **U.S. Cl.**USPC ..... **D22/108**(58) **Field of Classification Search**

USPC D22/100, 101, 103, 104, 105, 108, 109, D22/110, 111, 199; D21/567, 573, 574,

D21/575

CPC F41A 23/02; F41A 35/00; F41C 23/04; F41C 23/12; F41C 27/22

See application file for complete search history.

CLAIM

The ornamental design for a stock for a gun, as shown and described.

DESCRIPTION

FIG. 1 is a perspective view of a stock for a gun in accordance with my new design, the stock for a gun being in a fully deployed configuration;

FIG. 2 is a front, left, bottom perspective view of the stock for a gun of FIG. 1;

FIG. 3 is a front view of the stock for a gun of FIG. 1;

FIG. 4 is a rear view of the stock for a gun of FIG. 1;

FIG. 5 is a left side view of the stock for a gun of FIG. 1;

FIG. 6 is a right side view of the stock for a gun of FIG. 1;

FIG. 7 is a top view of the stock for a gun of FIG. 1;

FIG. 8 is a bottom view of the stock for a gun of FIG. 1;

FIG. 9 is a rear, right, bottom perspective view of the stock for a gun of FIG. 1

FIG. 10 is another perspective view of the stock for a gun of FIG. 1, the stock for a gun being in a collapsed configuration;

FIG. 11 is a front, left, bottom perspective view of the stock for a gun of FIG. 10;

FIG. 12 is a front view of the stock for a gun of FIG. 10;

FIG. 13 is a rear view of the stock for a gun of FIG. 10;

FIG. 14 is a left side view of the stock for a gun of FIG. 10;

FIG. 15 is a right side view of the stock for a gun of FIG. 10;

FIG. 16 is a top view of the stock for a gun of FIG. 10;

FIG. 17 is a bottom view of the stock for a gun of FIG. 10; and,

FIG. 18 is a rear, right, bottom perspective view of the stock for a gun of FIG. 10.

The broken lines immediately adjacent the shaded areas represent the bounds of the claimed design. All broken lines are directed to environment and are for illustrative purposes only and form no part of the claimed design.
